DESIGN FOR A SHOWER CURTAIN HOOK

Jacob Z. Silverman, Brooklyn, N. Y.

Application January 24, 1942, Serial No. 105,407

Term of patent 14 years

To all whom it may concern:

Be it known that I, Jacob Z. Silverman, a citizen of the United States and resident of the Borough of Brooklyn, county of Kings, city and State of New York, have invented a new, original, and ornamental Design for a Shower Curtain Hook, of which the following is a specification, reference being had to the accompanying drawing, forming part thereof.

Fig. 1 is a side elevation of a shower curtain hook showing my new design.

Fig. 2 is a front view of the same.

Fig. 3 is a rear view of the same.

The essential features of my design reside in those portions illustrated in full lines.

I claim:

The ornamental design for a shower curtain hook, substantially as shown and described.

JACOB Z. SILVERMAN.
